[57] CLAIM

The ornamental design for a combined computer copyholder with paper clamp, as shown and described.

DESCRIPTION

FIG. 1 is a perspective view of a combined computer copyholder with paper clamp showing my new design, wherein portions thereof have been obscured for convenience of illustration;

FIG. 2 is a bottom perspective view; and

FIG. 3 is a side elevational view thereof.

The undisclosed rear surface of the combined computer copyholder with paper clamp is conventionally flat and unornamented.

The computer depicted by means of broken lines in FIG. 1 is shown for illustrative purposes only.

FIG. 1.

FIG. 2.

FIG. 3.
